UNITED STATES PATENT OFFICE.

JOSEPH W. BARNA AND NATHAN A. THOMAS, OF CHICAGO, ILLINOIS.

PERFORATING MACHINE.

Application filed December 1, 1926. Serial No. 151,913.

This invention relates to improvements in eyeleting machines employed for setting eyelets in shoe-uppers and other articles with which eyelets are used.

- 5 The object of the invention is to provide means in a machine of this character for positively displacing or discharging the punchings from the die spindles and guiding them to a suitable point of deposit.
- 10 In machines of this general type now well known the eyelets are fed from a suitable reservoir or receptacle by a raceway to the setting mechanism, which differs somewhat in design and operation in the single set machine and in the duplex set machine. These parts may be of any well known construction to operate in the usual manner, and as they form no part of the present invention except in so far as they are necessary to the operation of the machine they need not be particularly described. In either type of machine each set has associated therewith a positively operated spindle-die which coacts with a punch block to cut an aperture in the material in which the eyelet is to be attached, and also means to pick up and hold an eyelet in position for the affixing operation of the set. The spindle-dies, which cut the apertures in the material in which the eyelets are to be affixed, are tubular or hollow, and the punchings are crowded upwardly therein by the pressure of succeeding punchings and escape from the upper ends of the spindles; in the single set machines a lateral opening is provided in the spindle above the die and the punchings are shaken out through this opening by the movement of the spindle, while in the duplex machines the ends of the spindles opposite the dies are open and the punchings are crowded out of the open ends of the spindles. In either case the punchings are discharged and scattered at random about the machine, and frequently lodge between the shoe uppers and their linings where they cause bumps and swellings when the shoe is lasted, and their removal requires considerable time and labor as well as liability to damage the work.
- 45 By our invention these objections are obviated and the punchings are confined and guided from the dies to the place of deposit.
- 50 Our invention consists of the organizations and arrangements of parts hereinafter fully described, particularly designated in

the claims, and illustrated in the accompanying drawings in which the same reference numerals indicate the same or similar parts in the several views.

In the drawings Figure 1 is a view in front elevation of part of a single-set eyeleting machine provided with the features of our invention; Figs. 2 and 3 are sectional views taken on the lines 2-2 and 3-3, respectively, in Fig. 1; and Fig. 4 is a detail perspective view of the guide shown in the above views.

Referring to Fig. 1, the reference numeral 10 designates a punch-block carried on the work-plate of the machine and having a set-punch 11, and 12 is a punch-bar reciprocably mounted in a head 13 supported above the block and carrying at its lower end in line with the set-punch a hollow spindle 14 which is provided with a female die 15 operating in conjunction with the punch 11 to cut apertures in the shoe material. The punch-bar is reciprocated toward and away from the punch-block by a suitable mechanism which is well known and so is not shown. The die-spindle 14 is hollow to receive the punchings cut from the material by the die in its successive strokes, and the spindle is provided with a lateral discharge opening 16 above the die. A cylindrical set-collar 17 is fixed around the spindle at the opening 16; in the exemplification shown the collar is split at one side and one of its wings 18 is threaded to receive a screw-bolt 19 by which it is clamped in place on the spindle. The collar is provided with a tubular lateral conduit 20 whose bore registers with the discharge opening 16 of the spindle, and a flexible pipe 21 is connected with the free end of the conduit 20 to convey the punchings away from the spindle to any place where it is desired to deposit them. A guide is located in the spindle to deflect the punchings out of the latter through the opening 16 and into the conduit 20. This guide may be of any suitable form and construction that will cause the punchings as they accumulate in the spindle to pass out through the discharge opening, and in the form here shown it consists of a thin metallic plate 22 secured at its outer end by a screw 23 to the collar 17 and extending through the opening 16 into and across the bore of the spindle where it is bent downwardly at an angle to present an inclined or cam sur-

face to the leading punchings as they are crowded up into the spindle by the following successive punchings.

The guides extend transversely of the bores of the spindles and their inclined operative faces displace or deflect the leading punchings out of the discharge orifices of the spindles and through the conduits as they are pushed or crowded against the guides by the following punchings, so that there is no choking or stoppage of the punchings in the spindles and this waste matter is passed and conveyed away from the machines and from the material in which the eyelets are fixed by the machines.

We claim:

1. In an eyeleting machine, a die adapted to cut apertures and having a hollow spindle

provided with a lateral discharge orifice, a collar on the spindle having a conduit in extension of the orifice, and a deflecting guide on the collar and extending into the orifice and transversely of the hollow spindle.

2. In an eyeleting machine, a die adapted to cut apertures and having a hollow spindle provided with a lateral discharge orifice, a collar on the spindle having a conduit in register with the orifice, and a deflecting guide consisting of a metallic plate secured at its outer end to the collar and extending through the discharge orifice of the spindle and downwardly across its bore.

In testimony whereof we affix our signatures.

JOSEPH W. BARNA.
NATHAN A. THOMAS.
